United States Patent Office

Des. 232,561
Patented Aug. 27, 1974

232,561

TWO-WAY RADIO OR SIMILAR ARTICLE

Martin C. Stessel, Schaumburg, Ill., assignor to
Motorola, Inc., Franklin Park, Ill.

Filed Mar. 26, 1973, Ser. No. 344,686

Term of patent 14 years

Int. Cl. D14—03

U.S. Cl. D26—14 K

FIG. 1

FIG. 2

FIG. 3

FIG. 4

FIG. 5

FIG. 1 is a front, top and right side perspective view of a two-way radio or similar article showing my new design;

FIG. 2 is a front elevational view;

FIG. 3 is a left side elevational view;

FIG. 4 is a rear elevational view; and

FIG. 5 is a bottom plan view.

I claim:

The ornamental design for a two-way radio or similar article, substantially as shown.
